UNITED STATES PATENT OFFICE.

FRANK T. CLARK, OF LUTHER, OKLAHOMA.

PEANUT-DIGGER.

1,162,137.

Specification of Letters Patent. Patented Nov. 30, 1915.

Application filed December 5, 1914. Serial No. 875,677.

To all whom it may concern:

Be it known that I, FRANK T. CLARK, a citizen of the United States of America, residing at Luther, in the county of Oklahoma and State of Oklahoma, have invented certain new and useful Improvements in Peanut-Diggers, of which the following is a specification, reference being had therein to the accompanying drawing.

10 This invention relates to peanut diggers and has for its object the production of a simple and efficient digger whereby the digging scoop may be regulated according to the depth which it is desired to be dug.

15 Another object of this invention is the production of a simple and efficient means for pulling the vines upwardly as the machine travels forwardly and also facilitating the changing of the angle at which the picking fingers are adapted to operate.

20 A still further object of this invention is the production of a simple and efficient means for dumping the vines in a collected heap after the peanut vines have been drawn 25 from the digging scoop.

With these and other objects in view this invention consists of certain novel combinations, constructions, and arrangements of parts as will be hereinafter fully described 30 and claimed.

35 In the accompanying drawings:—Figure 1 is a top plan view of the machine showing the seat and seat supporting rail removed therefrom. Fig. 2 is a longitudinal section taken on line 2—2, of Fig. 1. Fig. 3 is a transverse section taken on line 3—3, of Fig. 1, the wheels being shown in elevation. Fig. 4 is a perspective view of the scoop and scoop supporting means. Fig. 5 is a side elevation of the lever actuating means for changing the angle of the dragging fingers. Fig. 6 is a section taken on line 6—6, of Fig. 1. Fig. 7 is a section taken on line 7—7, of Fig. 1. Fig. 8 is a longitudinal section taken 40 on line 8—8, of Fig. 1, showing the manner in which the gear shield is supported upon the frame. Fig. 9 is a longitudinal section taken through the main supporting frame showing the manner in which the rake operating lever is connected to the pivotally 45 mounted rake carried by the rear of the machine.

50 By referring to the drawings it will be seen that 1 designates the main frame which 55 converges toward the front thereof and con-

stitutes a pair of parallel lips 2 for engaging the beam 3. A quadrant 4 is supported upon the rear end of the beam 3 and upon this quadrant 4 is mounted a lever 5. A shaft 6 is keyed to the lever 5, and this shaft 60 is provided with off-set ends 7, which ends 7 engage the upwardly extending ears 8 of the scoop supporting frame 9. The scoop supporting frame 9 is provided with a forwardly extending end 10 which end is pivotally connected to the lower end of the hanger 11 as clearly illustrated in Fig. 2.

65 The sides of the scoop supporting frame 9 are bent downwardly toward the rear ends thereof, and these rear ends engage a substantially V-shaped scoop member 12, which scoop member is preferably formed of sheet metal or other desired material. A plurality of rearwardly extending slightly curved fingers 13 are connected to the rear end of 70 the scoop blade 12 as clearly illustrated in Figs. 1, 2 and 4 for the purpose of constituting an efficient support for the peanut vines after the same have been dug from the ground. It should be understood that the 75 depth of the scoop 12 may be regulated by moving the lever 5 forward or backwardly in view of the fact that the frame 9 is supported upon the shaft 6, which shaft is keyed to the operating lever 5.

80 A seat supporting frame 14 is carried upon the main frame 1, and this seat supporting frame 14 carries a seat 15. A quadrant 16 is fixedly secured to the seat supporting frame 14 and a lever 17 is pivotally 85 mounted upon the quadrant 16. A guide frame 18 is pivotally mounted upon the seat supporting frame 14 and is provided with a plurality of apertures 19 through which the upper ends of the drag fingers 20 extend. 90 These drag fingers 20 are pivotally connected to the crank shaft 21, which crank shaft extends transversely of the frame 1 and when operated, will cause the drag fingers 20 to have a picking action for drawing 95 the vines rearwardly over the fingers 13 of the scoop 12 as is clearly illustrated in Figs. 1 and 2. A link 22 is connected to the lever 17 and also to the guide frame 18 so as to allow the angle of the guide frame 18 100 to be adjusted when so desired and permit the angle of the drag fingers 20 to be adjusted according to the desire of the operator.

105 By means of the adjustment of the guide 110

frame 18 it will be seen that the drag fingers 20 may be caused to have a substantially longitudinal or rearward pull upon the vines passing over the scoop 12 or the frame may 5 be so adjusted as to cause the drag fingers to have a substantially upward lifting action upon the vines.

One end of the crank shaft 21 is provided with a pinion 23 which pinion meshes with 10 an internally toothed gear 24, which gear 24 is carried by the main axle 25, the main axle 25 supporting the main frame 1. It will, therefore, be seen that an efficient means has 15 been produced for the purpose of driving the crank shaft 21. A shield 26 is supported upon the frame 1 by means of brackets 27 and overhangs the internally toothed gear 24 to constitute a protector therefor, and shield the same against foreign objects falling 20 upon and injuring the gear 24.

A lever 28 is pivotally mounted upon the main frame 1, and this lever is provided with a foot engaging lip 29 to allow the operator to engage the lever 28 with his foot for the 25 purpose of facilitating the operation thereof. A handle 30 is provided at the upper end of the lever 28 to allow the lever to be efficiently operated. A rearwardly extending link 31 is secured to the lever 28 and is also secured to 30 the upwardly extending ear 32 carried by the rake frame 33. This rake frame 33 is pivotally connected to the rear of the main frame 1 and is provided with curved rake teeth 34 for the purpose of receiving the vines after 35 the same have been forced from the rearwardly extending bars or teeth 13 of the scoop 12. It should be understood that when a sufficient number of vines have been collected upon the curved teeth 34, the vines 40 may be dumped in one heap in the rear of the machine by forcing the lever 28 for-

wardly and drawing the rake teeth 34 to the position shown in dotted lines in Fig. 2.

From the foregoing description it will be seen that a very simple and efficient device has been produced for the purpose of digging peanuts or other articles of like nature, and that further a very simple and efficient means has been produced for supporting and dumping the vines after the same have been 50 dug.

Having thus described the invention what is claimed as new, is:

1. A device of the class described comprising a main frame, a digging scoop, said scoop provided with a plurality of spaced fingers, a seat supporting frame, a guide frame pivotally mounted upon said seat supporting frame, a plurality of drag fingers, a crank shaft supporting said drag fingers, said drag fingers extending through said guide frame, and means for actuating said crank shaft. 55

2. A device of the class described comprising a main frame, a seat supporting frame carried thereby, a guiding frame pivotally mounted upon said seat supporting frame, drag fingers passing through said guiding frame, a scoop carried by said main supporting frame, said drag fingers adapted to drag vines from said scoop, and a lever carried by said seat supporting frame and engaging said guide frame for regulating the angle of said guide frame whereby the drag fingers may be caused to have either a rearward or upward pull upon the vines 70 passing over said scoop. 75

In testimony whereof I hereunto affix my signature in presence of two witnesses.

FRANK T. CLARK.
